UNITED STATES PATENT OFFICE.

CHARLES H. PATTEN, OF PROVIDENCE, RHODE ISLAND, ASSIGNOR TO REX MANUFACTURING CO., OF PROVIDENCE, RHODE ISLAND, A CORPORATION OF RHODE ISLAND.

BRACELET HOOK.

Application filed February 24, 1925. Serial No. 11,180.

To all whom it may concern:

Be it known that I, CHARLES H. PATTEN, a citizen of the United States, residing at Providence, in the county of Providence and State of Rhode Island, have invented certain new and useful Improvements in Bracelet Hooks, of which the following is a specification.

This invention relates to an improved construction of bracelet hook employed primarily for attaching the ends of a bracelet to a wrist watch and the like; and the object of this invention is to provide an operating member on the hook-closing tongue arranged to extend through the back of the hook to be engaged to lift the tongue from closed position to permit the ready detachment of the hook from the watch.

With these and other objects in view, the invention consists of certain novel features of construction, as will be more fully described, and particularly pointed out in the appended claims.

In the accompanying drawings:

Figure 1 is a perspective view of my improved hook showing the operating member extending through the back of the hook into position to be engaged to lift the tongue from closed position.

Figure 2 is a perspective view illustrating the under side of the tongue removed from the hook member.

Figure 3 is a perspective view showing the hook with the tongue removed showing the opening in its back.

Figure 4 is a sectional side elevation illustrating one form of tongue as mounted in the body of the hook, the free end of the tongue is shown in position to close the hook and as having an operating extension projecting through the back of the hook by means of which the tongue may be lifted from closed position.

It is found in the practical operation of ordinary bracelet hooks, somewhat difficult to place the finger inside of the bracelet beneath the tongue to lift the same sufficiently to remove the hook from the watch bail when the bracelet tightly engages the wrist of the wearer, which action sometimes serves to twist the bracelet to such an extent as to rupture some of its links. To obviate this difficulty, I have formed a finger on the end of the tongue and arranged the same to extend through the back of the

hook into position to be readily engaged so that the tongue may be lifted from its closed position to permit the hook to be readily disengaged from the bail of the watch to which it is connected; and the following is a detailed description of the present embodiment of my invention showing one construction by which these advantageous results may be obtained:—

With reference to the drawings, 10 designates the bracelet hook having a body portion 11 preferably formed in box shape with a forwardly-extending shank portion 12 having its end bent over into hook form as at 13, the back of this shank portion being herein shown as being provided with an opening 14 for the purpose presently described.

In the body portion of this hook, I have mounted a hook closing tongue member 15 which may be secured in the body portion 11 of the hook by any suitable means and may be provided with a spring tongue 16, if desired, or other suitable spring means for pressing the free end 17 of the tongue into engagement with the hook 13, to normally close the same. The free end of this tongue is preferably provided with a finger, extension member or operating shank 18 set at an angle to the plane of the tongue to extend up through the opening 14 in the back of the hook and the free end of this shank 18 above the back of the hook is preferably offset at an angle to the plane of the shank, as at 19, to be readily engaged by the finger nail of the operator to lift the tongue from engagement with the hook and so avoid the difficulty of being obliged to extend the finger around beneath the hook to engage and lift the tongue when it is desired to remove the hook from engagement with the bail of the watch.

My improved device is extremely simple and practical in construction and effective in its operation and by its use the closing tongue member may be readily withdrawn from closed position when desired to enable the hook to be disengaged from the watch or other device to which it is connected.

The foregoing description is directed solely towards the construction illustrated, but I desire it to be understood that I reserve the privilege of resorting to all the mechanical changes to which the device is susceptible, the invention being defined and

limited only by the terms of the appended claims.

I claim:

1. In a sheet metal bracelet hook having a body portion, a spring tongue fixed at one end to said body with its opposite free end normally closing the hook and having a portion projecting through the back of the hook to be engaged to lift the tongue from closed position.
2. A sheet metal bracelet hook formed of a body portion having a hook at one end with an opening through its back, and a hook-closing tongue having adjacent its free hook closing end an operating finger bent up and extending through said opening to be engaged to lift the tongue from closed position.
3. A sheet metal bracelet hook formed of a body portion having a hook at one end with an opening through its back, and a hook-closing tongue having one end housed and held in said body by the folding of the same into box shaped position and an operating finger on said tongue bent up and extending through said opening to be engaged to lift the tongue from closed position.
4. A sheet metal bracelet hook comprising a body portion having a hook-shaped shank with a hole through its back, a tongue extending from said body with its free end

normally yieldingly closing said hook and having an extension bent-up from adjacent its free end projecting through said hole to be engaged to lift the tongue from closed position.

5. A bracelet hook comprising a sheet metal body portion having a hook-shaped shank with an opening through its back adjacent the bend of the hook, a sheet metal spring-actuated tongue having one end mounted in said body its opposite end normally yieldingly closing said hook and having an integral finger at its free hook closing end extending at an angle therefrom through said opening to be engaged to lift said tongue to open position.

6. A bracelet hook comprising a sheet metal body portion having a hook-shaped shank with an opening through its back, a spring pressed sheet metal tongue mounted in said body with one end normally closing said hook, an integral finger folded up from the hook-closing edge of the tongue having a shank portion extending at an angle thereto through said opening, the end of said finger shank being offset at an angle to its shank portion to be engaged to lift the tongue to open position.

In testimony whereof I affix my signature.

CHARLES H. PATTEN.
